DESIGN FOR A COVER FOR AN INSTRUMENT CASING

Veron S. Thomander, Maplewood, and Robert H. Lewis, West Orange, N. J., assignors to Westinghouse Electric and Manufacturing Company, a corporation of Pennsylvania

Application April 11, 1942, Serial No. 106,556

Term of patent 14 years

To all whom it may concern:

Be it known that we, Veron S. Thomander and Robert H. Lewis, citizens of the United States, residing, respectively, at Maplewood and at West Orange, in the county of Essex and State of New Jersey, have invented a new, original, and ornamental Design for a Cover for an Instrument Casing, of which the following is a specification, reference being had to the accompanying drawing, forming a part thereof, in which:

Figure 1 is a plan view of the cover for an instrument casing embodying our new design, and

Fig. 2 is a view thereof in edge elevation.

We claim:

The ornamental design for a cover for an instrument casing, substantially as shown.

VERON S. THOMANDER.

R. H. LEWIS.
